UNITED STATES PATENT OFFICE.

SAMUEL LIPPINCOTT GRISWOLD KNOX, OF MILWAUKEE, AND WALTER FERRIS, OF SOUTH MILWAUKEE, WISCONSIN, ASSIGNEES TO THE BUCYRUS COMPANY, OF SOUTH MILWAUKEE, WISCONSIN, A CORPORATION OF WISCONSIN.

LOWER TUMBLER AND LADDER END FOR ELEVATOR-DREDGES.

SPECIFICATION forming part of Letters Patent No. 770,011, dated September 13, 1904.

Application filed January 21, 1904. Serial No. 190,001. (No model.)

To all whom it may concern:

Be it known that we, SAMUEL LIPPINCOTT GRISWOLD KNOX, residing in the city of Milwaukee, and WALTER FERRIS, residing in the 5 city of South Milwaukee, county of Milwaukee, Wisconsin, both citizens of the United States, have invented certain new and useful Improvements in Lower Tumblers and Ladder Ends for Elevator-Dredges; and we do hereby 10 declare the following to be a full, clear, and exact description of the invention, such as will enable others skilled in the art to which it appertains to make and use the same.

Our invention relates to certain new and useful 15 improvements in lower tumbler mechanism for elevator-dredges; and it consists in the details of construction and the combinations of parts hereinafter described, and illustrated in the accompanying drawings, in which—

20 Figure 1 is a side elevation of the lower end of a dredge-ladder supporting the lower tumbler including our improvements. Fig. 2 is a transverse section of the same.

In the operation of elevator dredging-machines 25 the inclined ladder or girder, which is hinged at its upper end to a stationary structure or boat, is provided at its respective ends with rotating tumblers or chain-wheels driven from a suitable source of power, which wheels 30 carry an endless chain having dredging-buckets attached thereto. The lower end of the ladder is lowered to the river-bottom, and the dredging-buckets dig or scrape out the material as they pass around the lower tumbler.

35 The lower end of the ladder is forked in order to support the tumbler-shaft, one arm of the fork passing down each side of the tumbler beyond the main body of the ladder and serves to support one of the tumbler-shaft bearings.

40 As heretofore constructed the ladder loses much of its strength at the beginning of this fork, where it is virtually cut in two to accommodate the tumbler, and from this point to the extreme lower end of the fork-section it 45 is very weak laterally. The dredge is anchored so that it cannot back off from the

gravel or other material to be dug, and a line is attached to the ladder near its lower end in order to pull the dredge-buckets sidewise into the bank to cause them to dig out the hard 50 material. In this way very heavy lateral strains are put upon the ladder at its weakest point—to wit, the fork which supports the lower tumbler—which frequently results in the spreading of the fork and the rapid 55 deterioration of the mechanism supported thereby. The lower tumbler is constantly running in muddy water, which carries in suspension a large amount of grit or sand, which works into the bearings upon which the tumbler rotates and cuts them out very rapidly. Various devices have heretofore been employed in the attempt to render these bearings water-proof, or at least grit-proof, to prevent this latter difficulty; but so far as we are aware 60 65 none of these devices have accomplished the desired object. The primary cause of the difficulty aforesaid arises from the springing of the ladder ends under the strain of the breasting-rope, as above described, the effect 70 of which is to pull the ladder ends apart sufficiently to loosen the rubber backing or other material and permit the water and grit to gain access to the bearings. In addition to these inherent faults of former tumbler constructions 75 it has been found very difficult in practice to keep the rubber rings or fibrous packing of the lower tumbler from being torn out by small stones, which are carried in and ground against the packing by the rotation of 80 the tumbler.

The object of our invention is to overcome the several difficulties above mentioned which are met in former tumbler constructions and to provide a combination of elements which 85 will produce a much stronger fork for the lower tumbler and a grit-proof bearing for the latter so constructed and arranged that while the parts may be readily removed or replaced, should occasion demand, the durability and 90 efficiency of the apparatus is greatly increased.

Referring to the drawings, *a* indicates the

lower end of the dredge-ladder, to which are secured the lateral bearing-brackets *b b*, in which the lower tumbler is journaled. The tumbler, which preferably consists of two sections *f f*, is rigidly secured to a hollow shaft *e*, which is supported in journal-boxes *g g*, mounted in recesses in the respective brackets *b*. To facilitate the assembly and adjustment of the members of the tumbler, the brackets *b b* are provided with removable caps *d d*, which are secured to the brackets by means of bolts *s* passing through lugs on the brackets and caps, respectively. It will be noted that the portion of the bracket which forms the bearing for the tumbler-shaft and the coöperating cap each constitutes a generally semicylindrically shaped shell having its edge which meets the coöperating part accurately milled to form a water-tight joint, and the two parts when assembled form a hollow chamber or cavity in which the corresponding journal-box *g* is mounted. Each of said journal-boxes *g*, which conforms generally to the interior contour of the recess in the bracket, is provided with a peripheral bearing surface or ridge *i*, which engages a corresponding groove or depression in the interior of said chamber to permit the journal-box to have a slight rocking movement to accommodate any deviation of the shaft from its true position due to strain on the mechanism. In order to hold the bearing-brackets which constitute the fork of the ladder at a fixed distance apart, a tie-rod *k* is passed through the hollow shaft *e* and is provided at its respective ends with head portions, which are secured to the respective brackets. In the particular form of the invention shown these head portions consist of flanges or bosses *l l*, which accurately fit into circular recesses, one half of each of said recesses being formed in the lower face of bracket *b* and the other in the contiguous face of cap *d*, so that when the parts are assembled the ends of the tie-rod are rigidly locked between the bracket and cap sections and serve to prevent the legs of the fork from moving toward or from each other. It is to be observed, of course, that any other suitable form of connection between the tie-rod ends and the fork sides could be employed. For example, the ends of the rod could be grooved to engage corresponding ribs in the recesses of the fork sides.

A rubber packing-ring *n* is mounted between the contiguous faces of each fork member and the tumbler and serves to exclude water and grit from the bearings. This ring is preferably formed as a folded rubber gasket with a strengthening-wire and is clamped firmly in place when the fork members are drawn up by the tie-rod. A guard-ring *o* is mounted outside of the packing-ring and is preferably formed of two pieces, one secured to the bracket *b* and the other to the cap *d*, and

serves to exclude sand or small stones which would work in between the tumbler and the adjacent fork member as the tumbler rotates. This guard - ring is secured in position by screws *p* and fits accurately in the space between the fork member and the adjacent tumbler-face.

Lubricating oil or grease is supplied to the tumbler-bearings by pipes *q q*, connected to a source of supply on the upper end of the ladder or upon the dredge-boat above the surface of the water. Each of said pipes communicates with the space around one of the journal-boxes *g* and thence by oil-holes *r* and suitable grooves in the bearing-box to the tumbler-shaft.

The advantages incident to the above construction are in part as follows: The tie-bolt *k* serves to accurately and rigidly hold the respective sides of the ladder-fork at a fixed distance apart, and any strain that is received by one member of the fork is immediately communicated to the opposite member thereof, thus practically doubling the strength of the fork to resist bending strains. This tying together of the fork members prevents the bearings from being thrown much out of line, and consequently prevents the opening of gaps between the sides of the tumbler and the fork members, which would permit grit and water to pass into the bearings. The annular bearing-surface *i* on each of the journal-boxes *g* serves to support said journal-box, which carries the weight of the tumbler and takes up the digging strains and permits a slight change in the alinement of the bearings as the ladder end is deflected as a whole under varying loads, and the end surface *m* of each of said boxes, which is in contact with the bottom of the recess in the bracket *b*, serves to transmit lateral thrust strains through the tumbler-shaft to the opposite bracket. The arrangement of the bearings whereby the tumbler-shaft is supported at its extreme ends distributes the end thrust caused by forcing the tumbler into the gravel most advantageously at points where the lubrication is best and at the greatest possible distance from those points where water or grit would tend to seep in in spite of the best packing.

Having thus described our invention, what we claim, and desire to secure, is—

1. In a lower tumbler mechanism for dredging-machines and the like, the combination of a hollow rotating tumbler-shaft, brackets in which said shaft is supported, and a tie-rod passing through said shaft and secured to said brackets to hold the latter at a fixed distance apart.

2. In a lower tumbler mechanism for dredging-machines and the like, the combination of a hollow tumbler-shaft, brackets in which said shaft is supported, removable caps on said brackets, and a tie-rod passing through said shaft and secured at its ends between the

brackets and caps, whereby the tie-rod is rigidly held in place and the brackets are held at a fixed distance apart.

5 3. In a lower tumbler mechanism for dredging-machines and the like, the combination of a hollow tumbler-shaft, brackets embracing one half of the shaft ends, removable caps embracing the other half of said shaft ends, and a tie-rod passing through said shaft, said tie-rod having heads on its ends engaging mating recesses formed in the contiguous faces of the respective brackets and caps, whereby the tie-rod is rigidly held in place and the brackets are held at a fixed distance apart.

15 4. In a lower tumbler mechanism for dredging-machines and the like, the combination of a hollow tumbler-shaft, brackets in which said shaft is supported, a tie-rod passing through said shaft and secured to said brackets to hold the latter at a fixed distance apart, and a removable journal-box for said shaft supported in each of said brackets.

25 5. In a lower tumbler mechanism for dredging-machines and the like, the combination of a hollow tumbler-shaft, brackets in which said shaft is supported, a tie-rod passing through said shaft and secured to said brackets to hold the latter at a fixed distance apart, and a removable journal-box for said shaft supported in each of said brackets, each of said journal-

boxes having a rocking bearing in its supporting-bracket to accommodate any deviation of the shaft under strain.

6. In a lower tumbler mechanism for dredging-machines and the like, the combination of a hollow tumbler-shaft, a tumbler mounted thereon, brackets in which said tumbler-shaft is supported, a tie-rod passing through said shaft and secured to said brackets to hold the latter at a fixed distance apart, and packing-rings held between the adjacent faces of the tumbler and the brackets.

35 7. In a lower tumbler mechanism for dredging-machines and the like, the combination of a hollow tumbler-shaft, a tumbler mounted thereon, brackets in which said tumbler-shaft is supported, a tie-rod passing through said shaft and secured to said brackets to hold the latter at a fixed distance apart, packing-rings held between the adjacent faces of the tumbler and the brackets, and a guard-ring secured in position between the tumbler and the brackets outside of the packing-ring.

40 45 In testimony whereof we affix our signatures in presence of two witnesses.

SAMUEL LIPPINCOTT GRISWOLD KNOX.
WALTER FERRIS.
